CLAIM

The ornamental design for a drain spade, as shown and described.

DESCRIPTION

FIG. 1 is an isometric view of a drain spade;

FIG. 2 is a top side view of a drain spade;

FIG. 3 is a bottom side view of a drain spade;

FIG. 4 is a back side view of a drain spade;

FIG. 5 is a front side view of a drain spade;

FIG. 6 is a right side view of a drain spade; and,

FIG. 7 is a left side view of a drain spade.

The broken line showing of the spade is for the purpose of showing portions of the article and forms no part of the claimed design.
